UNITED STATES PATENT OFFICE

WILLIAM A. BRYANT, OF MIAMI, FLORIDA, ASSIGNOR TO NEW WAY LUGGAGE CARRIER CO., OF MIAMI, FLORIDA, A CORPORATION OF FLORIDA

LUGGAGE CARRIER

Application filed May 13, 1930. Serial No. 452,013.

This invention aims to provide a luggage carrier for the running-boards of vehicles, so constructed that one of its members can be used as a step plate, as a barrier for preventing an article from sliding off the running-board, or as a clamp for holding an article on the running-board and against the vehicle body, at the will of an operator. A further object of the invention is so to construct the device that there will be no denting of the running-board, when the barrier is in a vertical position, the barrier being held securely in that position. A further object of the invention is to supply novel means for holding the barrier in adjusted positions with respect to the running board and to the article which is to be retained thereon.

It is within the province of the disclosure to improve generally and to enhance the utility of devices of that type to which the present invention appertains.

With the above and other objects in view, which will appear as the description proceeds, the invention resides in the combination and arrangement of parts and in the details of construction hereinafter described and claimed, it being understood that changes may be made in the precise embodiment of the invention herein disclosed, within the scope of what is claimed, without departing from the spirit of the invention.

In the accompanying drawings:

Figure 1 is a rear elevation with parts in section;

Figure 2 is a section on the line 2—2 of Figure 1;

Figure 3 is a vertical section showing the stop mechanism;

Figure 4 is a front elevation wherein parts are broken away;

Figure 5 is a section on the line 5—5 of Figure 1.

The numeral 1 marks the running-board of a motor vehicle, and 2 the body of the vehicle. Hinge strips 3 are disposed transversely of the running board, on top thereof, and are secured to the running-board by bolts 23 or otherwise.

At the edge of the running-board 1, the hinge strips 3 have tubular bearings 4 and 5

which are slit transversely at 6 to form tongues which extend inwardly at 7, and downwardly at 8, in contact with the edge of the running board, to form abutments. The bearing 5 has ratchet teeth 9 on its outer end. 55

The numeral 10 marks a foldable wing, preferably a metal plate, which serves as a tread plate when it is swung over horizontally in the direction of the arrow A in Figure 2, on top of the running board 1. When the wing 10 is disposed vertically, as in Figure 2, it serves as a barrier preventing an article 29 from sliding off the running board. Moreover, the wing 10 may be swung in the direction of the arrow A in Figure 2 to assume various angles, and to clamp an article in the angle defined by the running board 1 and the body 2, an observation which will be made more clearly manifest as the description proceeds. 70

Hinge strips 11 and 12 extend transversely of the wing 10, near to the ends of the wing, and are secured at 30 to the wing. At its inner end, the strip 11 has an eye 14, the strip 12 having a corresponding eye 15. The eye 14 has a lateral collar 16 provided with teeth 17 adapted to cooperate with the teeth 9 of the bearing 5. The parts 9 and 17 constitute interengaging elements for holding the wing 10 at adjusted angles with respect to the running board 1. 80

A shaft 18 is secured in the eyes 14 and 15. The shaft or hinge pintle 18 can rotate and slide longitudinally in the bearings 4 and 5. A compression spring 19 surrounds the shaft 85 18 and abuts against the eye 15 and the adjacent bearing 4 to hold the ratchet teeth 9 and 17 releasably interengaged.

Adjacent to the shaft 18, the wing 10 has an inwardly extended flange 20 adapted to engage the abutments 8 to hold the wing 10 in a vertical position, as in Figure 3. By providing the parts 20—8 of Figure 3, the edge of the running board 1 is not dented, and a positive abutment is provided which keeps the wing 10 in a vertical position and prevents the wing from gradually inclining outwardly in the direction of the arrow B in Figure 3. The wing 10 is offset at 25, near to its vertical edges, to leave room for 100

the hinge strips 11 and 3 and 12, when the wing 10 is folded in the direction of the arrow A in Figure 2 to lie flat on the running board 1 and to serve as a tread plate.

5 A torsion spring 21 is disposed about the shaft 18, one end 22 of the spring bearing against the edge of the running board 1, and the other end 24 of the spring bearing against the flange 20 of the wing 10 below the shaft 18. The tendency of the spring is to swing the wing 10 in the direction of the arrow A in Figure 2.

10 There are openings 26 in the wing 10 near to its ends, straps 27 being looped through the openings 26 and being joined by a buckle 28.

15 When the wing 10 is in a vertical position, as in Figure 2, the flange 20 of the wing, and the abutments 8 form a positive stop for the wing, the ratchet teeth 9 and 17 being interengaged to hold the wing releasably in a vertical position. The straps or securing devices 27 may be coupled by the buckle 28 around the article 29 on the running board.

20 25 The operator can move the wing 10 and the shaft 18 endwise to disengage the teeth 17 and 9, and the wing 10 then can be folded down on the running board 1 to serve as a tread plate. The wing 10 can be swung in the direction of the arrow A in Figure 2 to serve as a clamp, binding an article in the angle defined by the body 2 and the running board 1, the wing being held in inclined, clamping position by the spring 21. The 30 35 spring 21, furthermore, prevents the wing 10 from rattling when it is folded over on the running board 1 to serve as a tread plate.

40 45 If the operator wishes an unusually long luggage carrier, he can put two or more of the devices shown in Figure 1 on the running board in tandem, unbuckle the straps 27 from the position of Figure 1, extend them laterally in the direction of the arrows C of Figure 1, and couple them by the buckles 28 to the straps of corresponding devices, this being a matter of mere duplication, readily understood without an illustrative drawing.

I claim:

50 In a device of the class described, bearings attachable to the running board of a vehicle, the bearings being slit transversely, and the material freed by the slitting being extended downwardly to form abutments, a foldable wing, and a shaft mounted in the bearings 55 and carrying the wing, the wing comprising an inclined portion which engages the abutments to hold the wing in a substantially vertical position.

55 60 In testimony that I claim the foregoing as my own, I have hereto affixed my signature.

WILLIAM A. BRYANT.
